UNITED STATES PATENT OFFICE.

LOUIS N. D. WILLIAMS, OF OGONTZ, PENNSYLVANIA, ASSIGNOR OF ONE-HALF TO ROBERT W. SCOTT, OF PHILADELPHIA, PENNSYLVANIA.

KNITTING-MACHINE.

No. 853,668.

Specification of Letters Patent.

Patented May 14, 1907.

Application filed April 21, 1903. Serial No. 153,710.

To all whom it may concern:

Be it known that I, LOUIS N. D. WILLIAMS, a citizen of the United States, residing in Ogontz, Montgomery county, Pennsylvania, have invented certain Improvements in Knitting-Machines, of which the following is a specification.

My present invention consists of an improvement in the knitting machine for which Letters Patent No. 714,998, were granted to Robert W. Scott and myself on the 2nd day of December, 1902, as assignees of David C. Bellis, the object of my present invention being to so construct a machine of the character specified in said patent as to cause it to produce a fabric, which, while of the same general character as the fabric produced on said patented machine, differs specifically therefrom, said improved fabric forming the subject of application for patent filed by me of even date herewith.

In the accompanying drawings:—Figure 1, is a sectional view of sufficient of a knitting machine to illustrate my present invention; Fig. 2, is a sectional view, on a larger scale, of part of the machine, illustrating one of the operations of the same; Fig. 3, is a plan view of the needle dial and needle cylinder of the machine; Fig. 4, is an inverted plan view of the dial cam plate, and Fig. 5, is a view of the cams of the cylinder cam box, displayed on a flat plane.

The machine, in its general construction, is similar to that of the prior patent, the vertical needle cylinder being represented at 1, the needle dial at 2, the cylinder cam box at 3, and the dial cam plate at 4. The needle cylinder and dial may be stationary and the cam carrier may be caused to rotate, or the reverse construction may be adopted if desired.

A series of yarn guides 5 are employed for feeding yarn to the cylinder needles and a lesser number of yarn guides 6 are employed for feeding yarn to the dial needles, there being in the present instance, six cylinder yarn guides 5 and three dial yarn guides 6, as shown in Fig. 4, the cylinder cam box having, as shown in Fig. 5, a number of sets of cams corresponding with the number of cylinder yarn guides, and the dial cam plate having, as shown in Fig. 4, a number of sets of cams corresponding with the number of dial yarn guides, so that the needles of the cylinder and dial will be projected to receive

the yarn from their respective guides, the cylinder needles being projected when the dial needles are retracted, as shown at the right hand side of Fig. 1, and the dial needles being projected when the cylinder needles are retracted, as shown at the left hand side of Fig. 1.

Owing to the fewer number of dial yarn guides and the fewer number of sets of dial plate cams as compared with the yarn guides and cams of the cylinder, the fabric formed upon said dial needles will have a correspondingly lesser number of courses of stitches and it will also have a lesser number of wales of stitches, for, as will be observed on reference to Fig. 3, the dial has a lesser number of needle grooves than the cylinder, having in the present instance only half as many, hence the fabric produced upon the machine shown and described will have in one web, namely that produced upon the dial needles, only half as many wales of stitches and half as many courses of stitches as the fabric produced upon the cylinder needles. By reason of this construction coarse yarns can be used in connection with the dial needles and yarn guides, and such yarns can be composed of linen or other fiber possessing much less flexibility than cotton or wool, thus permitting of the use, for one of the webs of the fabric, of yarns of a character which cannot be used in machines of fine gage.

Certain of the dial needles have longer stems and shorter butts than others, these long stemmed dial needles being acted upon by a cam 7 of the dial cam plate so as to be projected at such a point as to receive yarn from one of the cylinder yarn guides 5, thereby forming upon these special dial needles loops or stitches of yarn drawn from the other web and serving to tie the two webs together at appropriate intervals, the knitting cams of the dial cam plate being recessed as shown in Fig. 2 so as to permit of this desired projection of the special dial needles without, however, losing control of the other and longer-butted dial needles at that point.

It is immaterial what fractional relation the needle grooves and yarn guides of the dial bear to the needle grooves and yarn guides of the cylinder, although in practice we have found that good results are attained when the cylinder has twice as many needles, yarn guides, and sets of operating cams as the dial.

The advantage of my invention may, in a measure, be obtained by employing a lesser number of dial yarn guides or a lesser number of dial needles, only in respect to the yarn guides and needles of the cylinder instead of employing a lesser number of both dial yarn guides and dial needles, although the latter construction is preferred.

It will be evident that my invention can be embodied in a machine which is practically the reverse of that shown and described, that is to say, one in which the reductions apply to the number of cylinder needle grooves and cylinder yarn guides, as compared with the corresponding elements of the dial structure, although such reductions can best be made in connection with said dial structure.

Having thus described my invention, I claim and desire to secure by Letters Patent:

1. A knitting machine in which are combined two sets of needles, carriers therefor, a series of yarn guides and cams operating in conjunction with the needles of one carrier, a lesser number of yarn guides and cams operating in conjunction with the needles of the other carrier, and means whereby certain of the needles of one set may, at intervals, be caused to engage with yarn normally fed to the needles of the other set, substantially as specified.

2. A knitting machine in which are combined two sets of needles, one set comprising a lesser number of needles than the other, carriers for said two sets of needles, cams operating upon each set of needles, guides feeding yarn to each set of needles independently, and means whereby certain of the needles of one set may, at intervals, be caused to engage with yarn normally fed to the needles of the other set, substantially as specified.

3. A knitting machine in which are combined two sets of needles, one set comprising a lesser number of needles than the other, carriers for said sets of needles, a series of yarn guides and cams co-operating with the set of needles comprising the greater number, a lesser number of yarn guides and cams co-operating with the set of needles comprising the lesser number, and means whereby certain of the needles of the set having the lesser number may, at intervals, be caused to engage with yarn normally fed to the needles of the other set, substantially as specified.

co-operating with the set of needles comprising the lesser number, and means whereby certain of the needles of one set may, at intervals, be caused to engage with yarn normally fed to the needles of the other set, substantially as specified.

4. A knitting machine in which are combined two sets of needles, carriers therefor, a series of yarn guides and cams operating in conjunction with the needles of one carrier, a lesser number of yarn guides and cams operating in conjunction with the needles of the other carrier, and means whereby certain of the needles of the set having the lesser number of yarn guides and cams may, at intervals, be caused to engage with yarn normally fed to the needles of the other set, substantially as specified.

5. A knitting machine in which are combined two sets of needles, one set comprising a lesser number of needles than the other, carriers for said two sets of needles, yarn guides and cams co-operating with each set of needles, and means whereby certain of the needles of the set having the lesser number may, at intervals, be caused to engage with yarn normally fed to the needles of the other set, substantially as specified.

6. A knitting machine in which are combined two sets of needles, one set comprising a lesser number of needles than the other, carriers for said sets of needles, a series of yarn guides and cams co-operating with the set of needles comprising the greater number, a lesser number of yarn guides and cams co-operating with the set of needles comprising the lesser number, and means whereby certain of the needles of the set having the lesser number may, at intervals, be caused to engage with yarn normally fed to the needles of the other set, substantially as specified.

In testimony whereof, I have signed my name to this specification, in the presence of two subscribing witnesses.

LOUIS N. D. WILLIAMS.
